EDWIN COULSON, OF CHISWICK, LONDON, ENGLAND

KNIFE-GRINDING MECHANISM FOR USE WITH SLICING MACHINES

Application filed May 7, 1928, Serial No. 275,926, and in Great Britain June 1, 1927.

This invention has reference to improvements in or relating to knife grinding mechanism for use with slicing machines and relates more particularly to slicing machines of the rotary disc knife and reciprocating carriage type.

In connection with slicing machines it is usual to provide a grinding mechanism for the knife comprising a pair of rotatably mounted grinding wheels disposed on either side of the knife and set at the requisite angle for effecting a grinding operation on the edge of the knife when brought into operation.

In grinding devices of the aforesaid type it is desirable that the reciprocating carriage carrying the slicing platform should be disconnected from the knife driving mechanism during a grinding operation as otherwise the out of balance effect occasioned by the reciprocation of the carriage tends to cause an uneven grinding of the edge of the knife. Furthermore, it is desirable that the grinding wheels should be maintained at a definite angle relatively to the knife-edge and that they should exert a definite and preferably constant pressure on the knife-edge. It is also desirable that provision should be made for the adjustment of the grinding wheels relatively to the knife in order to compensate for the wear of the grinding wheels and of the knife-edge.

The present invention has for its object the provision of an improved means of mounting and actuating the grinding mechanism of slicing machines of the aforesaid type whereby the aforesaid desiderata are obtained.

The invention consists of an improved grinding mechanism for slicing machines of the type hereinbefore referred to, characterized by the interconnection of a means for bringing the grinding wheels into their acting position with a clutch device for coupling the carriage reciprocation mechanism to the driving shaft such that the operation of actuating the said means for bringing the grind-

ing wheels into the grinding position simultaneously effects a declutching of the carriage driving mechanism from the driving shaft.

The invention also resides in the provision of means for ensuring the correct positioning of the wheels relative to the knife-edge and in the means for permitting of an adjustment of the position of the wheels relatively to the knife to compensate for wear. The invention further resides in the details of construction and in the grinding mechanism as a whole.

The invention will now be described with particular reference to the accompanying sheet of drawings which illustrate the invention as applied to a slicing machine of the rotary disc knife and reciprocating carriage type.

In the drawings:—

Figure 1 is a part sectional end elevation of the grinding wheels and their supporting means.

Figure 2 is an elevation of the upper portion of a pillar or standard constituting the supporting means for the housing carrying the grinding wheels.

Figure 3 is a part sectional elevation of the mechanism for permitting of the simultaneous disconnection of the carriage reciprocating mechanism from the main driving mechanism when the grinding wheels are positioned for the grinding operation, and

Figure 4 is a detail view of the means for moving the grinding wheels into and out of contact with the knife-edge.

Mounted on a bracket bolted to the boss carrying the bearings for the knife axle is a tubular pillar or standard 5 the upper portion 5^a whereof is screw threaded and provided with a pair of vertically arranged diametrically opposed slots 5^b. Slidably mounted within the bore 5^c of the said pillar or standard 5 is a cylindrical support 6 the upper end whereof carries a housing 7 which

constitutes a support for the grinding wheels 8, 9 and their actuating mechanism as will be hereinafter more particularly described. Interposed between the lower end of the said support and the bottom of the bore of the pillar or standard is a coil spring 10 which normally tends to press the support in an upward direction. Within the lower portion of the support is formed a cylindrical hole through which is passed a pin 11 of a greater length than the outer diameter of the threaded portion of the pillar or standard 5, said pin being adapted to be located and to slide within the slots formed in the upper end of the said pillar or standard. The upper side of the pin abuts the underface of a screw cap 12 adapted to engage with the threaded portion 5^a of the pillar or standard 5 for the purpose of securing the support 6 to the pillar or standard 5 whereby by screwing or unscrewing the cap 12 the height of the housing 7 relatively to the pillar or standard can be adjusted as required. The grinding wheels 8 and 9 are rotatably mounted on the ends of a pair of spindles 8^a, 9^a respectively which are slidably mounted within bearings formed in the housing 7. The grinding wheels, which as usual, comprise a main grinding wheel 8 and a finishing wheel 9 are provided with coil springs 13 and 14 which normally tend to maintain the wheels in contact with the edge of the knife 15. Adapted to bear on the end of the spindle 9^a of the finishing wheel 9 is the upper arm 16^a of a triple-armed bell crank lever the lower arm 16^b whereof bears on a flange 8^b secured to the end of the spindle 8^a of the main grinding wheel 8 the crank arm 16^c of the said lever being provided at its end with a horizontally disposed projection 16^d which carries a ball section 16^e adapted to be located within a tube 17 and to have motion in the said tube against the opposition of a coil spring 18 disposed within the said tube. The said tube 17 is provided along one side with a vertically disposed slot for permitting of the requisite motion of the projection carrying the ball.

Mounted in the upper end of the tube is a screw 19 the nose whereof impinges on the aforesaid ball section 16^e and admits of a variation of the setting of the crank arm 16^c of a triple-armed lever against the opposition of the coil spring 18 located within the tube.

The lower end of the aforesaid tube 17 is secured to the upper end of a rod 20 the lower end whereof is pivotally connected to the end of one arm of a lever 21 fulcrumed on a spindle 21^a secured to the base of the slicing machine. This lever 21 is provided adjacent the fulcrum with an upwardly extending crank 22 provided with a forked portion carrying inwardly directed pegs 22^a adapted to engage in a groove 23^a formed in the male member 23 of a clutch splined on the main driving shaft 24 of the machine, the female member 25 of

the clutch being loosely mounted on the said driving shaft 24 and having connection through a skew pinions 26, 27.

The skew pinion 27 is keyed on a vertically disposed spindle 27^a to the upper end whereof is attached one end of a crank arm 28^a and other end whereof is pivotally connected to one end of a connecting rod 28^c the other end whereof is pivotally connected to a projection 28^d, which is adapted to reciprocation on a pair of slides 28^e, one slide only being shown in the drawing. It will be seen that upon rotation of the skew pinion 27 the crank arm 28^a is rotated and effects through the connecting rod 28^c a reciprocation of the carriage 28. Adjacent its outer end the driving shaft has keyed thereon a bevel pinion 29 which meshes with a bevel pinion 30 mounted on a shaft having keyed thereto a sprocket wheel 31 which drives the knife 15 through the medium of a chain 32. Disposed about a large portion of the spindle 21^a is a coil spring 22^b, one end whereof is anchored to a fixed part of the machine and the other end whereof is adapted to bear on the crank arm 22 so as to tend to force the said arm so as to move the male member 23 of the clutch into engagement with the female member 25. The operating lever 21 is provided on its outer end with a knob 21^b the said lever also co-operating with a guide plate 33 provided with means for locating the control lever in one or other of its set positions. The said crank 22 on the control lever is arranged so that when the lever 21 is actuated to lower the grinding wheels 8 and 9 into contact with the knife-edge the said operation simultaneously effects a withdrawal of the clutch.

The operation of the device is as follows: When it is desired to effect a sharpening of the knife 15 the control lever 21 is moved in a downward direction thereby effecting an upward movement of the rod 20 connected to the other end thereof, the upward movement of the said rod 20 through the tube 17 effecting an anti-clockwise movement of the crank arm 16^c of the triple-armed lever whereby the arm 16^a in contact with the end of the spindle 9^a of the finishing wheel moves in a clockwise direction and allows the spring 13 disposed about the said spindle to bring the surface of the grinding wheel 9 into contact with the knife. Simultaneously the other arm 16^b of the said triple-armed lever moves in a clockwise direction away from the flange 8^b on the end of the spindle 8^a carrying the main grinding wheel 8 whereby the said wheel 8, under the agency of the coil spring 14, is forced into contact with the knife-edge. The movement of the operating lever 21 through the crank 22 also effects simultaneously a withdrawal of the male member 23 of the clutch and thereby frees the carriage reciprocation mechanism from driving connection with the main shaft 24 whereby the

knife 15 can be rotated for effecting a grinding operation without necessitating any reciprocation of the carriage. When the grinding operation has been completed the operating lever 21 is raised whereupon the rod 20 is moved in a downward direction thereby causing the upper arm 16^a of the triple-armed lever to bear on the end of the spindle 9^a carrying the finishing wheel 9 and to force the said wheel away from the knife 15 against the opposition of the coil spring 13, at the same time the lower arm of the triple-armed lever bears on the flange 8^b on the end of the spindle 8^a of the grinding wheel 8 and forces the said wheel 8 out of contact with the edge of the knife against the opposition of the coil spring 14.

It will be appreciated that in a construction hereinbefore described the grinding wheels 8 and 9 when in the grinding position are maintained in a definite position relative to the knife-edge and ensure a constant pressure thereon under the action of their respective coil springs. Moreover, the operation of positioning the grinding wheels automatically effects a de-clutching of the carriage traversing mechanism of the driving mechanism whereby the knife 15 can be rotated for effecting the grinding operation without the out of balance effect occasioned by the traverse of the carriage 28. Furthermore, the means for adjusting the setting of the crank arm 16^c of the triple-armed lever permits of a ready adjustment of the wheels to compensate for wear in the face of the wheels and, in addition, the provision of the means for adjusting the wheel supporting housing 7 admits of the ready adjustment of the position of the wheels as a whole to compensate for any wear so that the maximum amount of usage can be obtained from the grinding wheels.

Claims:—

1. A grinding mechanism for slicing machines of the rotary disc knife and reciprocating carriage type comprising a support, spindles slidably mounted relatively to said support, grinding wheels rotatably mounted on said spindles and adapted to be moved into and out of contact with the edge of the knife, projections on said spindles, a rockable triple armed lever the ends of one pair of arms whereof are adapted to bear on said projections, spring means adapted to bear on the spindles and adapted normally to tend to maintain the grinding wheels in contact with the knife edge, an actuating lever, means connecting the third arm of the triple armed lever to said actuating lever, a driving shaft for imparting rotary motion to the knife, a clutch member freely mounted on the driving shaft and in connection with the carriage reciprocation mechanism, a co-operating clutch member slidably but non-rotatably mounted on the driving shaft, an arm rigidly

connected to the actuating lever and in engagement with the slideable clutch member and adapted upon a movement of the actuating lever for causing the triple armed lever to permit the spring means to move the grinding wheels into contact with the knife edge to effect a simultaneous disengagement of the clutch and the consequential disconnection of the carriage reciprocation mechanism from the driving shaft during a grinding operation and means for varying the position of the triple armed lever relatively to the spindles carrying the grinding wheels for admitting of the adjustment of the position of the wheels relatively to the knife-edge in order to compensate for wear.

2. A grinding mechanism for slicing machines of the rotary disc knife and reciprocating carriage type comprising a support, a pair of grinding wheels rotatably and slidably mounted relatively to said support, means for moving said wheels into and out of contact with the knife edge, a rotatable driving shaft, means driven from said shaft for effecting a reciprocation of the carriage, a clutch member slidably but non-rotatably mounted on said driving shaft, an actuating means adapted to effect the engagement and disengagement of the said clutch member, means connecting said actuating means to the means for moving the grinding wheels into and out of their acting position the connection between the actuating means and the clutch member and between the actuating means and the grinding wheel control means being such that the operation of moving the said member for disengaging the clutch and thereby disconnecting the carriage reciprocation mechanism from the driving shaft simultaneously causes the member connecting the actuating means and the grinding wheel control means to cause the said grinding wheels to move into their acting position.

3. A grinding mechanism for slicing machines of the rotary disc knife and reciprocating carriage type comprising a support, spindles slidably mounted relatively to said support, grinding wheels rotatably mounted on said spindles, projections on said spindles, a rockable triple armed lever the ends of one pair of arms whereof are adapted to bear on said projections, spring means adapted to bear on the spindles and normally to tend to maintain the grinding wheels in contact with the knife edge, an actuating lever, means connecting the third arm of the triple arm lever to said actuating lever, a rotatable driving shaft, means driven from said shaft for imparting a rotary motion to the knife, means driven from said shaft for effecting a reciprocation of the carriage, a clutch member freely mounted on the driving shaft and connected to a part of the mechanism for effecting a reciprocation of the carriage, a clutch member freely but non-rotatably mounted on the driv-

ing shaft and adapted to be engaged and disengaged by the operation of said actuating lever the relation of the actuating lever to the clutch member and to the grinding wheel control means being such that the actuation of the said lever for disengaging the clutch simultaneously disconnects the carriage reciprocation mechanism from the driving shaft and causes the grinding wheel control means to move the grinding wheels into the acting position.

In testimony whereof I have hereunto set my hand.

EDWIN COULSON.
